DESIGN FOR A RECEPTACLE FOR PAPER
TISSUES AND THE LIKE

Raymond Munson and Irving M. Lax, New York,
and Milton Silverstein, Brooklyn, N. Y., assign-
ors to Harry Rothman, Brooklyn, N. Y.

Substitute for abandoned application Serial No.
70,626, July 24, 1937. This application April
22, 1939, Serial No. 84,490. Term of patent 14
years

to all whom it may concern:

Be it known that we, Raymond Munson, Irving M. Lax, and Milton Silverstein, citizens of the United States of America, residing, respectively, at New York, in the county and State of New York; New York, in the county and State of New York; and Brooklyn, in the county of Kings, and State of New York, have invented a new, original, and ornamental Design for Receptacle for Paper Tissues and the like, of which the following is a specification, reference being had to the accompanying drawing, forming part thereof.

This application is a substitute for our earlier application, Serial No. D. 70,626, filed July 24, 1937.

The design is characterized by a receptacle provided with an ornamental border, and a lip-

shaped opening with a lip-shaped flap closure, there being a border around the opening and on the flap closure, all as illustrated in the drawing.

In the drawing:

Fig. 1 is a plan view of a full size receptacle with the flap closed, and Fig. 2 is a perspective view of the same receptacle with the flap open, showing our new design. Fig. 3 is a cross sectional view of Fig. 2, along the line 3-3.

We claim:

The ornamental design for a receptacle for paper tissues and the like, as shown and described.

RAYMOND MUNSON.
IRVING M. LAX.
MILTON SILVERSTEIN.
